United States Patent Office

Des. 194,094
Patented Nov. 20, 1962

194,094

OVERHEAD GARAGE DOOR

Cecil R. Wolf, 201 8th Ave., and John P. Holland,
229 Ave. F, both of Rock Falls, Ill.

Filed June 22, 1959, Ser. No. 56,472

Term of patent 14 years

(Cl. D13—1)

FIG. 2

FIG. 1 is a front elevational view of an overhead garage door showing our new design; and

FIG. 2 is an enlarged vertical sectional view taken on the line 2-2 of FIG. 1.

We claim:

The ornamental design for an overhead garage door, substantially as shown.
